(57) **CLAIM**

The ornamental design for a surfboard bottle opener, as shown and described.

DESCRIPTION

FIG. 1 is a top view of a surfboard bottle opener in accordance with the present invention;

FIG. 2 is a bottom view of the surfboard bottle opener shown in FIG. 1;

FIG. 3 is a left side view of the surfboard bottle opener shown in FIG. 1;

FIG. 4 is a right side view of the surfboard bottle opener shown in FIG. 1;

FIG. 5 is a front view of the surfboard bottle opener shown in FIG. 1; and,

FIG. 6 is a rear view of the surfboard bottle opener shown in FIG. 1.

The broken lines depict environmental subject matter only and form no part of the claimed design.
